*Olds & Unham,
Reciprocating Saw Mill.
Patented Dec. 26, 1810.*

14074 *Dec 26, 1810 457*
Ezekiel Old & Henry Upsham.

Letters Patent.

The Schedule referred to in these Letters Patent and making part of the same, containing a description in the words of the said Ezekiel Old & Henry Upsham, themselves or an improvement in a sawing Machine invented by them and patented the twenty-first day of December one thousand eight hundred and nine.

This improvement consists in the application of the moving principle of the Machine above mentioned, to the sawing or slitting of logs &c. into boards, planks or denailing and is effected in the following manner. The saw with its moveable frame, and other immediate appendages may be such as in the common saw mill, or in any other way which fancy may dictate. But in this case, instead of removing the saw frame and saw by a crank, as in the common mode the action and reaction of the saw are produced by a lever, or lever the opposite extremity being in the zigzag groove of a cylinder, such as specified in the Schedule of the Patent above mentioned; except that the said grooved cylinder is in this improvement shifted from a horizontal to a vertical position. a crank and fly wheel may also be added or not at the option of the constructor.
